US00D939170S

(12) United States Design Patent (10) Patent No.: US D939,170 S
(45) Date of Patent: * Dec. 21, 2021

(54) IRONING BOARD WITH IRON STAND

(71) Applicant: LG ELECTRONICS INC., Seoul (KR)

(72) Inventors: Kyutae Park, Seoul (KR); Hoi Jeon, Seoul (KR); Youngsoo Ha, Seoul (KR); Kyungah Lee, Seoul (KR); Jaeil Bae, Seoul (KR)

(73) Assignee: LG Electronics Inc., Seoul (KR)

() Term: 15 Years

(21) Appl. No.: 29/752,854

(22) Filed: Sep. 29, 2020

(30) Foreign Application Priority Data

Apr. 17, 2020 (KR) 30-2020-0017186

(57) CLAIM

We claim the ornamental design for an ironing board with iron stand, as shown and described.

DESCRIPTION

FIG. 1 is a perspective view of an ironing board with iron stand showing the new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a perspective view showing a state of use thereof.

The broken lines shown in FIG. 8 are for the purpose of illustrating environment and form no part of the claimed design.

1 Claim, 8 Drawing Sheets
